[57] CLAIM

The ornamental design for a propeller blades and hub, as shown and described.

DESCRIPTION

FIG. 1 is a top and rear perspective view of a propeller blades and hub showing my new design;

FIG. 2 is a left side elevational view thereof;

FIG. 3 is a rear elevational view thereof; and

FIG. 4 is a top plan view thereof, the bottom plan view being a mirror image of that shown.

A portion of the shaft is shown broken away to indicate indeterminate length and for convenience of illustration.
